UNITED STATES PATENT OFFICE.

HARRY B. McNULTY, OF CLEVELAND, OHIO.

DESIGN FOR A CABINET FOR TALKING-MACHINES.

45,467.

Specification for Design.

Patented Mar. 24, 1914.

Application filed February 7, 1914. Serial No. 817,356. Term of patent 14 years.

To all whom it may concern:

Be it known that I, HARRY B. McNULTY, a citizen of the United States, and a resident of Cleveland, county of Cuyahoga, and State of Ohio, have invented a new, original, and ornamental Design for Cabinets for Talking-Machines, of which the following is a specification, reference being had to the accompanying drawing, forming part thereof.

In said annexed drawing:—the single figure there appearing is a perspective view

of a cabinet for talking machines showing my new and ornamental design.

I claim:—

The ornamental design for a cabinet for talking machines, as shown.

Signed by me this 5th day of February, 1914.

HARRY B. McNULTY.

Attested by—

D. S. DAVIES,

JNO. F. OBERLIN.
